CLAIM

The ornamental design for a compartmented holder for bottles or the like, as shown.

DESCRIPTION

FIG. 1 is a front perspective view of a compartmented holder for bottles or the like showing our new design;

FIG. 2 is a top plan view thereof;

FIG. 3 is a right side view thereof;

FIG. 4 is a rear view thereof;

FIG. 5 is a bottom plan view thereof;

FIG. 6 is a sectional view thereof in an elevation taken on line 6—6 of FIG. 2;

FIG. 7 is a partial sectional view thereof taken on line 7—7 of FIG. 4.

FIG. 1.

FIG. 2.

FIG. 3.

FIG. 5.

FIG. 4.

FIG. 6.

FIG. 7.
